(57) CLAIM

The ornamental design for a dining table, as shown and described.

DESCRIPTION

FIG. 1 is a frontal perspective view of the dining table showing my new design;

FIG. 2 is a right elevational view thereof, the left elevational view being identical;

FIG. 3 is a front elevational view thereof, the rear elevational view being identical; and,

FIG. 4 is a top plan view thereof.

The bottom of the table, not shown, forms no part of the claimed design.
